UNITED STATES PATENT OFFICE.

ANKER S. LYHNE, OF BRIDGEPORT, CONNECTICUT.

VANITY BOX.

Application filed August 15, 1925. Serial No. 50,382.

This invention relates to vanity boxes, and has for an object to provide a box of this character which will be neat and attractive in appearance and may be easily carried in 5 a lady's hand bag, and especially is provided with an improved construction for carrying loose powder which is at all times available for use with a puff, and in which the supply of powder may be easily renewed.

10 With the foregoing and other objects in view, I have devised the construction illustrated in the accompanying drawing forming a part of this specification, similar reference characters being employed throughout the various figures to indicate corresponding elements. In this drawing,

Fig. 1 is a side elevation of my improved box in open position.

Fig. 2 is a top plan view thereof.

20 Fig. 3 is a vertical section through the box closed and on a somewhat enlarged scale.

Fig. 4 is a detail of a spring catch for removably holding the powder container in the box, and

25 Fig. 5 is a side elevation of the loose powder container removed from the box and with the cover raised.

The box comprises the usual body section 10 and cover section 11 hinged together at 30 one side by the hinge 12, the upper edge of the body preferably being reduced in diameter as shown at 13, so as to telescope into the open side of the cover section when it is in closed position to give a neat and attractive appearance and also a tight closure.

In one of these sections, preferably the bottom or body section, I mount a loose powder container comprising a body member 14 and a cover therefor 15. This container 40 is made of sheet metal and cupped as illustrated to form a receptacle for the loose powder 16, and is provided with an outwardly extending annular flange 17 about its upper periphery. This flange is also preferably turned downwardly at its outer edge as shown at 18 to form a short flange to give a neater appearance and facilitate mounting of the container in the box. This arrangement also greatly stiffens the flange 45 17 so that it is not easily bent out of shape.

The cover 15 is depressed at its central portion, as shown, and is of a size to fit into the body member 14, as shown in Fig. 3, and has an outwardly extending flange 19 55 which rests on the top of the flange 17 of the body member. This cover is hinged to

the flange 17 as indicated at 20, and on its opposite side is provided with a ring 21 for lifting the cover to give access to the container for refilling the container with 60 powder. The bottom of the depressed portion of the cover is provided with perforations 22 to allow passage of the powder from the container.

The container may be secured in the box 65 in various ways, but that shown is a simple and easily assembled means and allows for removal of the container if desired, and also allows for the easy insertion of a new container with fresh powder. This securing means comprises a projection on one side, in the present case, a spring 23 forming a catch for holding the cover 11 closed, this spring being secured to the side wall of the body 10 by any suitable means as a rivet 70 24. It is free to swing in at its opposite end where it carries a lug 25 to engage a slit or recess 26 in the side wall of the cover 11 to secure the cover in closed position, and it is provided with a lug 27 extending 75 through an opening in the wall of the body 10 where it may be pressed inwardly by the thumb of the user to release the catch and allow opening of the box. It will be noted in Fig. 3 that the outer periphery of 80 the flange 17 projects under the spring 23 so that this side of the container 14 is held against outward movement by this spring. On the opposite side of the box is a spring 28 which has a yieldable tongue 29 carrying 85 a lug or projection 30 which may extend over the top of the flange 17. This spring may be conveniently mounted by means of 90 ears 31 on the hinge member 32. In assembling, these ears are passed through 95 openings 33 in the side wall of the body 10 and then bent over the ends of the member 28, as shown in Fig. 4. It will be apparent that pressing the tongue 29 outwardly will 100 release the loose powder container and allow its removal from the box, and that it may be as easily returned to the box by merely inserting one edge under the spring 23 and pressing its opposite edge past the lug 30.

It will be noted that the shape of the 105 cover 15 forms a tight fit with the vertical walls of the body member 14, and at right angles to this the flanges 17 and 19 have another close fit. This arrangement forms a joint which will effectively prevent leakage 110 of the powder from the container. The depression in the cover also forms a recess or

- space for a powder puff 34 which is held in this depression when the box is closed by a mirror 35 mounted in a frame 36 hingedly mounted in the cover section at 37. This 5 mirror will press the wool side of the puff against the perforations 22 while the box is closed, effectively closing the perforations and preventing passage of the powder from the container to the remaining portions of 10 the box. Some of the powder will, however, pass to the puff in ordinary handling of the box so that it will be on the puff for ready application to the skin. More powder may be passed from the container to the puff by 15 merely tapping the cover with the puff or by inverting the box. The depressed portion of the cover also forms a convenient receptacle for any powder that may pass through the perforations and is not taken up by the puff, 20 the vertical walls of the cover preventing this powder passing into the other portions of the box or being spilled, and this powder is retained in the depression by the puff when the box is closed.
- 25 The frame 36 carrying the mirror may be hinged to a ring 38 mounted in the cover 11, which ring may have lugs 39 for engaging the edge of a compact 40, and the ring 38 may have a flange or rib 41 against which 30 the back of the mirror frame rests to form a closed compartment for this compact and the puff 42 for use therewith.
- Having thus set forth the nature of my invention, what I claim is:
- 35 1. In a vanity box, body and cover sections, means for retaining loose powder in one of the sections comprising a horizontally extending annular flange about an opening therein, a hinged cover for said opening depressed at its central portion to provide a wall about the periphery of said portion and at substantially right angles thereto to fit into said opening and provided with an outwardly extending flange at the outer edge 40 of said wall to rest on the first mentioned flange, said depressed portion of the cover forming a holder for a puff and provided with perforations in its bottom wall for passage of powder from the container to the 45 puff.
- 50 2. In a vanity box, body and cover sec-
- tions, a loose powder container mounted in one of the sections comprising a cupped member having an outwardly extending annular flange about its upper periphery, and 55 a hinged cover for said member, said cover being depressed at its central portion to provide a substantially cylindrical wall about the periphery of said central portion to fit into the cupped portion of the member and 60 provided with an outwardly extending flange at the outer edge of said wall to rest on the top of the first mentioned flange, said 65 depressed portion of the cover being provided with openings for passage of powder from the container.
3. In a vanity box, body and cover sections, a loose powder container mounted in one of the sections comprising a cupped member having an outwardly extending annular flange about its upper periphery, a 70 perforated hinged cover for said member depressed at its central portion to fit into the cupped portion of the member and provided with an outwardly extending flange to rest 75 on the first mentioned flange, and means for removably securing the container in said section comprising a projection on opposite sides of the container to engage the flange thereon, one of said projections being mounted 80 on a spring to yield outwardly to allow passage of the edge of said flange.
4. In a vanity box, hinged body and cover sections, a loose powder container for one of the sections comprising a cupped member 85 having an outwardly extending flange, a cover hinged to said flange and having a depressed central portion providing a side wall about the periphery of said central portion and substantially normal thereto to fit into 90 the cupped member and also having an outwardly extending flange at the outer edge of the side wall to rest on the flange of said member, said depressed portion of the cover forming a holder for a puff and provided 95 with perforations in its bottom wall for passage of powder from the container to the puff, and means for securing the container in one of the sections.

In testimony whereof I affix my signature.

ANKER S. LYHNE.
